UNITED STATES PATENT OFFICE.

THEODORE F. LEMASSENA, OF NEWARK, NEW JERSEY.

PUMP-VALVE.

SPECIFICATION forming part of Letters Patent No. 289,668, dated December 4, 1883.

Application filed December 16, 1882. (No model.)

To all whom it may concern:

Be it known that I, T. F. LEMASSENA, a citizen of the United States, residing in the city of Newark, county of Essex, and State of New Jersey, have invented certain new and useful improvements in Pump-Valves, fully described and represented in the following specification and the accompanying drawings, forming a part of the same.

10 This invention consists in a special construction for the lower end of a barrel-pump and the removable valve applied thereto.

The object of the invention is to provide a valve that may be removed without the use of 15 tools and without detaching the seat from the barrel; and the object is secured by making the valve of a circular piece of leather or india-rubber and securing it to the seat by a removable bridge clamped across the middle 20 of the valve, the bridge being held in place by a central bolt and cross-bar beneath the seat. The opposite segments of the valve thus form separate flaps hinged to the bridge, and the whole valve may be readily removed 25 after unclamping the bridge from the seat by folding the flaps together and withdrawing them endwise through the aperture in the seat.

In the drawings, Figure 1 is a section of the lower end of the pump-barrel, taken on line 30 xx in Fig. 2. Fig. 2 is a plan of the top of the valve and seat; Fig. 3, a bottom view of the same with the valve collapsed for insertion; Fig. 4, an alternative form for the bridge E, and Fig. 5 a bottom view of the valve and 35 seat.

The valve consists of the circular flange, of leather, rubber, or other suitable material, which may be supported under pressure of the water column by plates P P', such as are 40 shown riveted to the movable valve-flaps in Figs. 2 and 5. Such plates are not necessary in valves under two inches in diameter, as the support afforded by the bridge and the edges of the valve-seat is sufficient to resist the head 45 of water commonly applied to such pumps.

In the drawings, A is the barrel of an ordinary bilge or drainage pump broken off just above the seat. B is the seat usually soldered therein, and provided with feet B'. C C is the 50 double flap-valve; D, a bridge extended across

the upper surface of the same, and long enough to reach over the seat, so that its ends press the valve-piece thereon when the bridge is clamped. E is a lower bridge reaching in a similar manner across the lower side of the 55 seat, and F is a bolt passed through C, D, and E to clamp them all together, the seat B receiving the pressure. The bolt is shown in Fig. 3 provided with a nut upon the upper side of the bridge D, but in Fig. 1 is shown 60 secured therein by casting, and a thumb-nut, E', is shown secured upon the lower end, so that the bolt may be readily released to withdraw the valve.

In Fig. 1 a wedge or key is shown inserted 65 in a slot in the bolt beneath the bridge E, which construction is suitable for very large valves. In Fig. 1 the valve is shown clamped to the bridge D by an auxiliary plate, H, the latter being inserted between the opposite 70 edges of the seat C and held in place by a nut, H'. In the same figure the bridge D is shown provided with a steady-pin, G, at each end, extended through the valve C C into holes 75 formed in the seat B at the opposite ends of the bridge. These pins serve to guide the operator in placing the valve and bridge in the center of the seat when inserted through the aperture indicated at B' in Fig. 3, and the pins may be cast upon the bridge and holes 80 formed in the rubber flange to admit them.

The function of the plate H is to sustain the middle of the rubber or leather flange of which the valve is formed, its edges being sustained by the seat B under the pressure of the 85 water; but it also serves to unite the valve C and bridge D together during their insertion into the aperture B' and their adjustment upon the seat B. Such union, however, may be sufficiently secured by the pins G, and in such 90 case the lower bridge, E, may be made, as shown in Fig. 4, with a portion adapted to fit between the edges of the seat B, like the plate H, and thus support the valve-flange when in action.

95 From the above description it will be seen that the entire structure is formed without tapping any holes in the seat B or making any attachments thereto for securing the valve, the latter being held in place by the simple 100

bridges and bolt F, and being easily removed or replaced by an unskilled workman without any tools or special skill.

By my construction the seat-castings are 5 merely galvanized to prevent rusting, and are then ready to solder into the barrel A without any machine-work being required to prepare them at all.

I am aware that an expanding piston has 10 been patented on October 18, 1881, with a valve construction analogous to mine; but my invention is designed and adapted to secure a convenient removal of the valve from the interior of an almost inaccessible valve-seat, 15 while the object of the said piston construction was to furnish a means of compressing an elastic ring to fit a cylinder-bore, and was constructed for this purpose with circular metallic plates on both sides of such ring, instead 20 of the straight bridges I employ. I therefore disclaim the said patent, my invention including the barrel A and fixed seat B as part of its essential features.

Having thus set forth the nature and advantages both in simplicity of construction 25 and utility, I claim the same as follows:

1. The pump-barrel A, in combination with the fixed seat B and the removable pieces C, D, E, F, and F', the whole arranged and operated as herein shown and described.

2. The combination, with the removable double flap-valve C C and the seat B, of the bridge D, having steady-pins G, fitted to holes in the seat, and the plate H, clamped beneath the valve by the bolt F, as and for the purpose 35 set forth.

In testimony whereof I have hereunto set my hand in the presence of two subscribing witnesses.

T. F. LEMASSENA.
